UNITED STATES PATENT OFFICE.

JOHN W. FREE, OF WOODLAWN, PENNSYLVANIA, ASSIGNOR TO JONES & LAUGHLIN STEEL COMPANY, OF PITTSBURGH, PENNSYLVANIA, A CORPORATION OF PENNSYLVANIA.

METHOD OF BENDING SKELP.

1,374,146.

Specification of Letters Patent.

Patented Apr. 5, 1921.

Application filed August 24, 1920. Serial No. 405,758.

To all whom it may concern:

Be it known that I, JOHN W. FREE, residing at Woodlawn, in the county of Beaver and State of Pennsylvania, a citizen of the 5 United States, have invented or discovered certain new and useful Improvements in Methods of Bending Skelp, of which improvements the following is a specification.

My invention relates to improvements in 10 method for bending pipe skelp preparatory to welding, and more particularly to the bending of skelp for lap-welding and bringing it to tubular form with overlapped edges while in unheated condition.

15 In a companion application Serial No. 365,009, filed March 11th, 1920, I have described and claimed a mill in the operation of which the method is performed. In this application I shall describe and claim the 20 method as distinct from instrumentalities by which the operation is performed. However, since the method is performed in the operation of the mill alluded to, I shall now describe that mill and its operation.

25 In the accompanying drawings Figure I is a view of the mill in side elevation; Fig. II is a view of it in plan; Fig. III is a vertical transverse section, on the plane indicated by the line III—III, Fig. I; Fig. IV 30 is a view in elevation of one of the pairs of rolls detached; and Fig. V is a fragmentary view to larger scale, showing in elevation one of the guides for the material in its advance from one roll pass to another. Figs.

35 VI to XII inclusive show in vertical section the successive roll passes through which the material in the course of its fabrication passes, and associated with the rolls themselves the material is shown. Above the successive roll passes of the mill as shown in 40 Figs. I and II, I have placed the numerals VI, VII, VIII, etc., thus indicating to which roll pass each sectional view belongs.

The mill consists essentially of a succession of pairs of rolls, forming the succession of roll passes illustrated in Figs. VI to XII, inclusive. In Fig. II, I have applied the numerals 1 to 7 to the upper rolls there shown of this succession of pairs.

50 These rolls, it will be observed, are ar-

ranged all of them in parallel positions—in this instance they are all horizontal, and this arrangement makes possible the mounting of them all in a common frame or housing 8 and the driving of them, or at least so 55 many of them as are power driven, through the gear train 9 of simple arrangement, sufficiently indicated in Figs. I, II, and III. The intervals at which the successive roll pairs are set are conveniently short, and the 60 mill accordingly becomes a continuous mill (there is no appreciable elongation of the material under treatment). Ordinarily, a single length of material under treatment will in the course of treatment be engaged 65 by all or substantially all of the shaping rolls simultaneously.

Between successive roll pairs are arranged suitable guiding means, including the idle beveled rollers 10 mounted on vertical stub 70 shafts and placed in pairs between the passes. One of these guide rollers is illustrated in Fig. V and their positions are indicated in Figs. I and II.

At the delivery end of the mill straightening means are provided, and these preferably include a pair of rollers 11, which ordinarily need have no capacity for relative movement, but which are mounted to rotate idly in their bearings. Their faces 80 are properly shaped, and of a shape which will be more clearly defined in the sequel. This pair of rollers is, in order to accomplish its intended ends, mounted for adjustment as a unit, both vertically and horizontally. 85

Coming now to the skelp-shaping instrumentalities and their operation, the development of a skelp into a pipe blank will be sufficiently understood on careful consideration of Figs. VI to XII, with reference to 90 the other figures to make plain the roll-driving means.

First of all, it is to be observed that a flat skelp is developed by transverse bending into a tubular blank with overlapped edges: 95 a blank of proper shape and size, and with edges sufficiently overlapped, to undergo the welding operation and produce a lap-weld pipe of the intended dimensions. The bending of the blank is developed by beginning 100

with the skelp in horizontal plane and arching it upward. The blank as it develops is accordingly downwardly concave, and, by virtue of this position, it clears itself of scale between the roll passes.

Coming to particular definition of the roll passes, the preferred arrangement is as follows: the rolls of the first pass are shaped to develop a uniform curvature, across the 10 width of the skelp; in the second pass, the radius of the side portions of the now curved blank is diminished to a smaller dimension than the middle portion. At the same time, however, the middle portion also 15 is preferably reduced somewhat in curvature. In the third pass the curvature of the mid portion is reduced and the whole brought to uniform curvature, preferably to the curvature of the side portions in the 20 second pass; in the fourth pass the radius of the bottom of the now trough-shaped blank, the middle portion of the blank, is still further reduced. The lower roll of the 25 fourth pass is the last one to engage the inner surface of the developing blank; both rolls of the fifth pass engage the exterior surface, for the curvature of the blank has now, as will be seen in Fig. IX, developed until the angular sweep of the arc which the 30 blank forms, exceeds 180°. In the fifth pass the radius is reduced throughout and made substantially uniform, the two edges of the blank coming now into close proximity, so that the blank now assumes a tubular form. 35 The lower roll of the sixth pass is stepped, and in the sixth pass one edge of the blank is bent inward a distance as great as the thickness of the material, and this portion is thus reduced in radius of curvature and 40 brought to substantially its ultimate curvature; otherwise, there is no reduction of curvature in the sixth pass. The seventh pass reduces the radius of curvature of the remainder, constricts the tubular blank to 45 its ultimate dimensions, and brings the edges to the desired overlapped position.

All the roll pairs are preferably positively driven, excepting only the sixth, the 50 pair which effects the depression of one edge relatively to the other. I find it preferable to avoid a frictional tension of roll upon blank here; but instead mount the rolls of this pair for idle turning.

I desire to call attention to the fact that 55 all of the instrumentalities which act upon the material while in the course of formation to tubular shape ready for lap welding act upon it externally; there is no internal ball nor mandrel upon which the developing tube is shaped. This is a great simplification and, while my instrumentalities do 60 not forbid the use of such a ball or mandrel, I consider its absence a distinct and substantial advantage, and it is a thing not

known before in the preparation of blanks 65 for lap welding.

I desire further to note that the shaping instrumentalities engage and exert shaping stress upon and only upon the faces of the skelp, leaving the scarfed edges free of 70 stress, free of shaping contact with roll surfaces or with one another, and so unmarred and undamaged for the ultimate welding operation.

I have now described a mill which, in 75 its operation, performs the method of my present invention. The characteristic features of that method are pointed out in detail in the ensuing claims, and I wish to make plain the fact that the mill has been 80 described in an exemplary way as proper means for performing the method. Heretofore to the best of my knowledge and belief the bending of the skelp for lap-welding has involved, and has been supposed to require an initial heating of the material, and heretofore in the bending of skelp for lap welding, it has been the universal practice to bend the skelp over a mandrel, and to the best of my knowledge and belief the use 85 of a mandrel has been deemed to be essential to successful operation. In the practice of my invention I have, as is now apparent, made gain of manifest practical value in those respects. 90

95 I claim as my invention:

1. The method herein described of developing an unheated length of skelp into a tubular blank with overlapped edges, which consists in, first, bending the skelp transversely into a tubular blank of uniform radius, second, by externally exerted pressure resisted only by the rigidity of the material, reducing the radius of curvature of one margin of the blank to a greater degree 105 than the remainder, and finally, by externally exerted pressure resisted only by the rigidity of the material, reducing the radius of curvature of the remainder of the blank. 110

2. The method herein described of developing an unheated length of skelp into a tubular blank with overlapped edges, which consists, first, in bending the skelp transversely into an arc-shaped blank of uniform curvature, second, developing the curvature of the marginal portions of the blank to curves of less radius than the medial portion, third, reducing the radius of curvature of the medial portion and bringing the whole to uniform curvature, fourth, reducing the 115 radius of curvature of the medial portion while that of the marginal portions remains unchanged, fifth, by compression exerted upon the external surface of the article and resisted only by the rigidity of the material itself, reducing the radius of curvature of the marginal portions and bringing the whole to uniformity again, sixth, by 120 125

externally exerted pressure resisted only by the rigidity of the material, reducing the radius of curvature of one margin to a greater degree than the remainder of the article, 5 and seventh, by externally exerted pressure resisted only by the rigidity of the material, reducing the radius of curvature of the remainder of the article.

In testimony whereof I have hereunto set my hand.

JOHN W. FREE.
